Harold D. Fetty, Birmingham, Mich., assignor to The Goodyear Tire & Rubber Company, Akron, Ohio, a corporation of Ohio

Filed Aug. 9, 1963, Ser. No. 76,162

Term of patent 14 years

(Cl. D90—20)

FIG. 1

FIG. 2

FIG. 3

FIG. 1 is a perspective view of a tire showing my new design, it being understood that the full line portion is repeated throughout the circumference of the tire, as shown by means of broken lines;

FIG. 2 is a cross-sectional view thereof; and

FIG. 3 is a plan view of a portion thereof.

The dominant features of my design reside in the portions shown in full lines.

I claim:

The ornamental design for a tire, as shown and described.
